UNITED STATES PATENT OFFICE.

JAMES SPEERS, OF WEST MANCHESTER, PENNSYLVANIA.

WATER-HEATER FOR STEAM-ENGINES.

Specification of Letters Patent No. 26,299, dated November 29, 1859.

To all whom it may concern:

Be it known that I, JAMES SPEERS, of West Manchester, in the county of Allegheny and State of Pennsylvania, have invented a new and useful Improvement in Water-Heaters for Steam-Engines; and I do hereby declare that the following is a full and exact description thereof, reference being had to the accompanying drawings and 10 to the letters of reference marked thereon.

Similar letters refer to similar parts.

The nature of my invention consists in furnishing the water heaters of steam engines which supply the force pump with 15 heated water with a self regulating waste valve, and also in dividing the heater into two compartments, and so arranging the pipe which conveys the water to the force pump which supplies the boilers with water 20 that it will receive from the top or near the top of the water in the heater, the whole being constructed in the manner and for the purpose hereinafter described.

To enable others skilled in the art to 25 make and use my invention, I will proceed to describe its construction and operation.

In the accompanying drawings, Figure 1 represents a central section of my improved heater. Fig. 2 represents a broken section 30 in perspective.

(It will be observed that a portion of one end and the side of the model is cut away so that the interior with the arrangement of its parts may be seen.)

35 (a) is the heater, (b) is the supply pipe for the force pump, the pipe (b) extends up into the heater so as to receive the hottest water which is always the uppermost in the heater, (c) is the waste pipe and is used 40 for carrying off the water when it rises above the desired height in the heater, and is furnished with a valve marked (o), and branch pipe marked (x), which extends up into the heater two or three inches higher 45 than the pipe marked (d), and enters pipe (c) on the outside of the heater below the valve (o). The lower end of pipe (c) is often immersed in water, when that is the case a vacuum is frequently formed in pipe 50 (c) below the valve (o) by the heated water passing through the pipe, and when a vacuum is formed below the valve (o), the valve becomes inoperative. The branch pipe (x) is used for the purpose of pre-

venting the formation of a vacuum in pipe 55 (c) below the valve (o), and in case the valve should become inoperative from any other cause the branch pipe will act conjointly with the pipe (c) in carrying off the surplus of water from the heater, so that the water 60 can in no case rise in the heater higher than the top of the branch pipe (x); (j) is the fulcrum of the lever (f), to the lever (f) is attached the valve stem (d) of valve (o), the lever (f) and float (h) are held in the 65 desired position by the stem (l) and guide (g) which is furnished with a slot for the lever (f), and an opening for stem (l), (k) is a partition which is placed between the pipe (b) and valve (o), this partition 70 (k) is used for the purpose of preventing the mud, dirt or sand from accumulating around or about the pipe (b), and it also aids in bringing the mud, dirt or sand in close proximity with valve (o), and pipe (c), which 75 is placed at the bottom of the heater.

The "escape or exhaust" steam from the cylinder of the engine heats the water in the heater and is conveyed into the heater by the pipe (n), (m) is the pipe which leads from 80 the "tank" or "cold water pump" to the heater, and supplies the heater with water. It will be observed that the part of branch pipe (x) which extends up into the heater 85 is represented by dotted lines, the pipes (m and n) are also represented by dotted lines.

A mud, dirt or sand chamber may be placed at the bottom of the heater near to or around the pipe (c), or at any other part 90 of the bottom desired.

The operation of my improvement is as follows: The pipe (b) which leads to the force pump is supplied from the uppermost water (which is always the hottest) in the heater and when more water than is desired 95 has entered the heater the float (h), will rise up, thereby opening the valve (o), and let the surplus water pass off through the pipe (c), and any mud, dirt or sand which 100 may have collected in the heater will be carried off with the surplus water.

I wish it to be clearly understood that my invention is for supplying the force pump of the steam engine with heated water which is forced by the pump into the boiler. 105 And I also wish it to be understood that my invention is not intended for an "indicator" of the height of the water in the boiler or

boilers or for opening the safety valve of steam boilers when the water becomes too low.

Having thus described the nature construction and operation of my improvement, what I claim as of my invention and desire to secure by Letters Patent of the United States is—

1. The arrangement of the float (*h*), lever (*f*), valve (*o*), partition (*k*), and pipes (*b*, *c*, and *x*), when arranged substantially as herein described for the purpose of con-

structing water heaters for supplying the force pump of steam engines with heated water.

15

2. The use of the branch pipe (*x*), when used in connection with pipe (*c*), and valve (*o*), as herein described and for the purpose set forth.

JAMES SPEERS.
